UNITED STATES PATENT OFFICE.

HERBERT AUSTIN, OF BROMSGROVE, ENGLAND.

MOUNTING AN AEROPLANE-PROPELLER AND CARRYING A GUN WHICH FIRES AXIALLY THROUGH THE PROPELLER.

1,329,156.

Specification of Letters Patent. Patented Jan. 27, 1920.

Application filed August 15, 1918. Serial No. 250,067.

To all whom it may concern:

Be it known that I, HERBERT AUSTIN, a subject of the King of Great Britain, and residing at Bromsgrove, in the county of Worcester, England, engineer, have invented certain new and useful Improvements in Mounting an Aeroplane-Propeller and Carrying a Gun Which Fires Axially Through the Propeller, of which the following is a specification.

According to this invention, an aeroplane propeller, together with the gear wheel by which it is driven from a gear wheel on the engine shaft, is rotatably mounted upon an arm which is supported from one end only and which is rigidly carried by the engine case and projects therefrom in a position in which it is clear away from the engine shaft, and preferably the gear wheel on the engine shaft gears directly with the gear wheel which surrounds the arm.

In practice the arm is fixed to the engine case at the top thereof, being conveniently clamped within halves of a socket which are formed, respectively, with halves of the case, and the inner or rear end of the arm is, preferably, carried back the whole distance along the top of the case within the valley which lies between the rows of inclined cylinders of an engine of the V-type, and, in such case, is clamped at both ends of the case between half sockets of the case. If it is required that a gun shall be used to fire axially through the propeller, the arm is formed tubular and the rear end extends beyond the rear pair of half sockets of the case and the gun is carried mainly by this extended portion of the arm.

In order that the invention may be clearly understood, I will now describe a practical application of the same, which is illustrated, by way of example, by the drawings herewith, of which:—

Figure 1 is a side elevation of as much as it is necessary to show of an aeroplane engine and propeller, the features of the invention being shown as they appear in a longitudinal section.

Fig. 2 is a section taken in the plane indicated by line 2—2 of Fig. 1; and,

Fig. 3 is a portion of the rear end elevation of the case, showing the rear pair of half sockets, and the inner end of the tubular arm, in section. In this view, the cylinders shown by Fig. 2 are omitted.

The hub A of the propeller A¹ is mounted to rotate about a tubular bar or arm which is supported from one end only, the portion B of which projects beyond the forward end of the crank-case C to the extent required to carry the propeller, and the inner portion B¹ of which passes lengthwise over the top of the crank-case along the valley which lies between the rows of inclined cylinders D of the engine; and this tube is carried at the forward end of the case by a pair of half sockets C¹ each of which is formed with the corresponding longitudinal half of the case, the tube being tightly clamped by the half sockets by the tightening up of bolts E which pass through both the half sockets and assist in fixing together the halves of the case. The rear end of the tube is similarly fixed by half sockets C². To the rear end of a backwardly-extending portion 75 of the hub A is fixed a gear wheel F which is axial therewith, and this wheel is driven from the engine crank-shaft G through the medium of a gear wheel F¹ on such shaft, which is shown as gearing directly with the wheel F. The propeller hub A and wheel F are carried by the forwardly projecting length B of the tube through the medium of a roller bearing H, at their inner end, and a roller bearing H¹ at their outer end, 85 and a ball bearing J, immediately in advance of the roller bearing H, takes the thrust of the propeller. This thrust is transmitted in one direction from a beveled surface a of the hub and in the other direction from a beveled surface k' of a steel ring k which revolves with the hub. m is a sleeve around which the inner ball race j of the thrust bearing fits and through the medium of which the inner race h of the bearing H is tightened against a collar a' of the tube by means of a nut n which is screwed upon the tube. The ball race j abuts against a flange of the sleeve m which itself abuts against the side of the race h. 100

A gun is shown, by Fig. 1, in position to fire through the arm. The barrel P, including a considerable portion of the length of the breach P¹, is a somewhat loose fit within the rear portion of the length of tube B¹. A mounting R is fixed, in any convenient manner, tightly around the portion of the rear end of the length of tube B¹ which projects somewhat beyond the rear end of the case C. This mounting has rigid 110

therewith the bar R^1 along which the gun is slidable for the recoil against the force of a spring r which surrounds the bar. The rear end of this bar is supported by suitably inclined struts, such as the strut S , from the rear end of the case C . p is a guide collar of the gun barrel P and is slidable within the tube B^1 .

Having fully described my invention, 10 what I claim and desire to secure by Letters Patent, is:—

1. In an aeroplane, the combination of an engine, a gear wheel on the engine shaft from which the drive is given off, an arm 15 which is supported from one end only and is rigidly carried by the engine case and projects therefrom in a position in which its axis is clear away from the axis of the engine shaft, a propeller and a gear wheel 20 which are rotatably mounted on the said arm, the said last-mentioned wheel receiving the drive and transmitting it to the propeller, substantially as set forth.
2. In an aeroplane, the combination of an engine, a gear wheel on the engine shaft 25 from which the drive is given off, an arm which is supported from one end only and is rigidly carried by the engine case and projects therefrom, a propeller and a gear wheel 30 which are rotatably mounted on the said arm, the said last-mentioned wheel gearing with the said wheel on the engine shaft and receiving the drive therefrom and transmitting it to the propeller, substantially as set forth.
3. In an aeroplane, the combination of an engine, a gear wheel on the engine shaft from which the drive is given off, an arm supported from one end only, half sockets 40 formed with halves of the engine case between which the said arm is clamped to fix it to the engine case, a propeller and a gear wheel which are rotatably mounted on the said arm, the said last-mentioned wheel receiving the drive and transmitting it to the propeller, substantially as set forth.

4. In an aeroplane, the combination of an engine, a gear wheel on the engine shaft from which the drive is given off, a tubular arm which is supported from one end only and is rigidly carried by the engine case in position to admit of a projectile being fired therethrough, a propeller and a gear wheel which are rotatably mounted on the said arm, the said last-mentioned wheel receiving the drive and transmitting it to the propeller, substantially as set forth.

5. In an aeroplane, the combination of an engine of the V-type, a gear wheel on the engine shaft from which the drive is given off, an arm supported from one end only and having a backward extension which is fixed at each end of the engine case and passes between its points of fixture along the valley which lies between the rows of inclined cylinders, a propeller and a gear wheel which are rotatably mounted on the said arm, the said last-mentioned wheel receiving the drive and transmitting it to the propeller, substantially as set forth.

6. In an aeroplane, the combination of an engine, a gear wheel on the engine shaft from which the drive is given off, a tubular arm supported from one end only and having a backward extension which is rigidly carried by the engine case, a propeller and a gear wheel which are rotatably mounted on the said arm, the said last-mentioned wheel receiving the drive and transmitting it to the propeller, a gun of which the barrel enters the rear end of the tubular arm and a mounting which is fixed around such end and has rigid therewith a bar along which the gun is slidable during recoil, substantially as set forth.

In witness whereof I have hereunto signed my name this 29 day of July, 1918, in the presence of two subscribing witnesses.

HERBERT AUSTIN.
